US00D804744S

(12) United States Design Patent (10) Patent No.: US D804,744 S
(45) Date of Patent: * Dec. 5, 2017

(54) ANIMAL WASTE PAIL

(71) Applicant: Lauren Cooper, Newark, NJ (US)

(72) Inventor: Lauren Cooper, Newark, NJ (US)

() Term: 15 Years

(21) Appl. No.: 29/555,326

(22) Filed: Feb. 20, 2016

(51) LOC (10) Cl. 30-99

(52) U.S. Cl.

USPC D30/161

(58) Field of Classification Search

CLAIM

I claim the ornamental design for an animal waste pail, as shown and described.

DESCRIPTION

FIG. 1 is a perspective view of the animal waste pail showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

1 Claim, 7 Drawing Sheets
